UNITED STATES PATENT OFFICE

2,488,677

FLUORESCENT LAMP SOCKET

Clyde D. McCann, Des Moines, Iowa

Application August 23, 1948, Serial No. 45,641

3 Claims. (Cl. 173—328)

1

The principal object of my invention is to provide a socket of fluorescent light tubes that permits both the rapid placement of a tube thereon or removal of a tube therefrom.

A further object of this invention is to provide a fluorescent light tube socket that eliminates the usual rotating of the tube to fasten and electrically connect it.

A still further object of my invention is to provide a fluorescent light tube socket that successfully makes and maintains electric contact with the contact points of the tube.

A still further object of this invention is to provide a fluorescent light tube socket that is economical in manufacture, durable in use and refined in appearance.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of a fluorescent light tube being held in two of my sockets and with dotted lines illustrating the placement or detachment of the tube in or from the sockets.

Fig. 2 is a side sectional view of my socket.

Fig. 3 is a cross-sectional view of the socket taken on line 3—3 of Fig. 2.

Fig. 4 is an exploded perspective view of my socket and more fully illustrates its construction.

Fig. 5 is a horizontal sectional view of the socket taken on line 5—5 of Fig. 2.

Fluorescent light tubes 10 have at each end two contact rod points 11 and 12. Many types of sockets have been produced to hold such light tubes. Obviously, two sockets are employed to hold a tube due to the fact that such tubes have two contact rod points at each end. Usually such sockets have receiving grooves for these points and the usual method is to place the tubes in place and then rotate the tube until electric contact is accomplished. Obviously, such an operation is not easy to perform and electrical contact is usually poor. I have overcome such objections by providing a socket that permits sliding of the tube therein for fastening, and a continuous yielding electric contact to the tube contact points.

Referring to the drawings I will now describe my socket, it being understood that with fluorescent light tubes a socket is required for each end of the tube. I have used the numeral 13 to des-

2

ignate the cup portion. These cup portions may be attached to a wall or ceiling by any suitable means, however, usually some kind of bracket is used. I have used the numeral 14 to designate a hollow bracket. Such brackets are usually secured to the cup by extending through a hole in the rear side portion of the cup and then riveted therein, or upset to provide a head 15. Usually a peripheral welt 16 is formed around the bracket arm just outside of the cup shell to prevent the bracket sliding further into the cup. Obviously, the head 15 formed on the end of the bracket prevents its withdrawal from the cup. Such construction makes a rigid support. The numeral 17 designates a collar slidably placed in the cup and having a cut out portion 18 to receive and embrace the head 15, as shown in Fig. 5. This construction prevents the independent rotation of the collar when in place in the bottom portion of the cup. The numeral 19 designates an inwardly turned flange on the forward marginal edge of the collar. Extending radially inwardly from the inner edge of the flange are two diametrically opposed lugs 20 and 21. The numeral 22 designates a sleeve slidably extending into the collar and having two evenly spaced apart longitudinally extending grooves 23 and 24 in its outer side wall for embracing the two lugs 20 and 21, respectively. By this construction the sleeve may slide inwardly and outwardly in the collar but is prevented from independent rotation thereto, due to the lugs 20 and 21, and the grooves 23 and 24. So that the sleeve may freely slide inwardly without contacting the bracket head 15, it has a cut-away portion 25 in its rear end portion, as shown in Fig. 4. The numeral 26 designates an inwardly turned flange on the forward end of the sleeve. The numeral 27 designates a plate of insulating material in the forward end 40 of the sleeve and to the rear of the flange 26. The numeral 28 designates a similar plate of non-conductive material on the front of the sleeve and forward of the flange 26. These two plates are secured together and to the forward end of the sleeve by bolts, rivets, or like 29. The numerals 30 and 31 designate two holes diametrically opposed to each other and extending through the plate 28, as shown in Fig. 4. The numerals 32 and 33 designate two contact members secured through the plate 27 and registering with the holes 30 and 31, respectively. The two electric lead wires 34 and 35 extend through the bracket, into the cup, and then are secured to the contact members 32 and 33, respectively. Sufficient slack of the flexible lead wires are pres-

ent in the cup to permit the sleeve to move forwardly and backwardly in the collar. The numeral 36 designates an outwardly turned flange on the rear marginal edge of the sleeve. This flange is capable of engaging the inwardly turned flange on collar for limiting the forward sliding movement of the sleeve. The numeral 37 designates a coil spring embracing the sleeve, having one end bearing on the flange on the forward end of the collar, and its other end bearing on the plate 28, as shown in the drawings. This spring yieldingly holds the sleeve in a forward position relative to the collar. To assemble the device it is merely necessary to force the collar and parts connected thereto into the cup, as shown in Fig. 2. The collar makes frictional contact with the inside wall of the cup. With two such sockets, properly held and spaced apart, it is a simple matter to attach a fluorescent light tube in and between the sockets. The tube end is pushed into one socket with its two contact rod points extending into the holes 30 and 31 of that socket. Obviously, this movement into the socket will force the sleeve of the socket inwardly and thereby permit the other end of the tube to move in front of the other socket. By permitting this other end of the tube to enter the second socket, its two contact ends will be aligned with and will enter the holes 30 and 31 of such second socket, thereby completing the electrical connection. As the springs of both sockets are similar in strength they will equalize each other and one end of the tube will be extending into one socket and its other end will be extending into the other socket, as shown in Fig. 1, thereby fastening the tube in the sockets. To remove the tube, it is merely necessary to force the tube in one direction so that its end will clear one of the sockets and then lift outwardly as shown by dotted lines in Fig. 1.

Some changes may be made in the construction and arrangement of my light socket without departing from the real spirit and purpose of my invention, and it is my intention to cover by my claims, any modified forms of structure or use of mechanical equivalents which may be reasonably included within their scope.

I claim:

1. In a fluorescent light socket, a cup, a hollow bracket extending into said cup and having a head inside said cup, a collar inside said cup and having a cut-away portion embracing said head, an inwardly turned flange on the forward end of said collar, a sleeve slidably extending into said collar, two longitudinal grooves in the outer side of said sleeve, two lugs formed on said flange extending into said two grooves, respectively, an outwardly turned flange on the rear end of said sleeve, an inwardly turned flange on the forward end of said sleeve, a plate on the inside forward end of said sleeve, a plate at the forward end of said sleeve; said two plates being of non-conductive material, a means for securing said two

plates together, two holes extending through said second plate, two contact members on said first plate and registering with said two holes, respectively, two electric lead wires extending through said bracket, into said cup and secured to said contact members, respectively, and a coil spring embracing said sleeve having one end bearing on said first mentioned flange and its other end bearing on said second mentioned plate.

10 2. In a fluorescent light socket, a cup, a hollow bracket extending into said cup and having a head inside said cup, a collar inside said cup and having a cut-away portion embracing said head, an inwardly turned flange on the forward end of said collar, a sleeve slidably extending into said collar, two longitudinal grooves in the outer side of said sleeve, two lugs formed on said flange extending into said two grooves, respectively, an outwardly turned flange on the rear end of said sleeve, an inwardly turned flange on the forward end of said sleeve, a plate on the inside forward end of said sleeve, a plate at the forward end of said sleeve; said two plates being of non-conductive material, a means for securing said two plates together, two holes extending through said second plate, two contact members on said first plate and registering with said two holes, respectively, two electric lead wires extending through said bracket, into said cup and secured to said contact members, respectively, a coil spring embracing said sleeve having one end bearing on said first mentioned flange and its other end bearing on said second mentioned plate, and a cut-away portion in said sleeve for clearance with said head.

35 3. In a fluorescent light socket, a cup, a hollow bracket extending into said cup and having a head inside said cup, a collar inside said cup and having a cut-away portion embracing said head, an inwardly turned flange on the forward end of said collar, a sleeve slidably extending into said collar, a means for yieldingly holding said sleeve forward relative to said collar, a non-conductive plate member secured to the forward end of said sleeve, two depressions in said plate member, a contact member at the bottom of each of said depressions, two electric lead wires extending through said bracket, into said cup and connected to said two contact members respectively, and a means for limiting the forward movement of said sleeve relative to said collar.
